UNITED STATES PATENT OFFICE.

WALTER PATON, OF CARLISLE, ENGLAND.

JACQUARD MECHANISM FOR LOOMS.

SPECIFICATION forming part of Letters Patent No. 682,115, dated September 3, 1901.

Application filed December 17, 1900. Serial No. 40,089. (No model.)

To all whom it may concern:

Be it known that I, WALTER PATON, a subject of the Queen of Great Britain, residing at Carlisle, in the county of Cumberland, England, have invented certain new and useful Improvements in Jacquard Mechanism for Looms; and I do hereby declare the following to be a full, clear, and exact description of the invention, such as will enable others skilled in the art to which it appertains to make and use the same.

This invention relates to harness-jacquards or shedding-motions of looms, and particularly to the two-cylinder machines for weaving cross-bordered or headed fabrics, such as carpet-squares, shawls, or fabrics with two patterns or figures or fancy goods.

The object of my invention is to produce an improved mechanism for automatically or self-actingly controlling the changing of the pattern card-cylinders at any predetermined point or points in the weaving of a fabric or at any interval of measurement of fabric woven—as, for instance, in weaving carpet-squares, shawls, or similar headed goods having a center portion and cross-borders woven alternately throughout the piece one cylinder will be maintained in operation until the center portion, which may measure two, three, or other number of yards between the cross-borders, is woven, and immediately such length is produced the cylinders will be changed and the other one maintained in operation until the width of the cross-bordered portions of adjacent squares have been woven, this change from cylinder to cylinder being effected either after weaving given lengths of fabric, as instanced above, or alternately in any other order at will, which avoids the employment of repeating ground-cards and brings about a considerable saving in the number of cards required for weaving squares, shawls, or figured or fancy goods.

Referring to the drawings, Figure 1 is an elevation of so much of a harness-jacquard as is essential to show the application of my improvements. Fig. 2 is an enlarged side elevation, looking in the direction of arrow A, Fig. 1, of the measuring-motion for controlling the changing of the cylinders after weaving any predetermined length of fabric. Fig. 3 is an elevation looking in the direction of arrow B,

Fig. 1, of part of the loom-frame, showing the gearing and chain-drive for rotating the measuring-motion one revolution during the weaving of any given length of fabric. Figs. 4 and 5 are details of supplementary attachments to be called upon when the measuring mechanism is not required for controlling the changing of the cylinders, respectively, in any order at will or alternatively every pick.

The same letters of reference denote corresponding parts throughout.

Referring to the drawings, letter *a* designates the framework of the jacquard; *b c*, the two pattern card-cylinders, arranged on the same side of the jacquard and each adapted as called for to act upon its respective set of jacquard-needles *b' c'*; *e e*, the hooked uprights or lifters; *f*, the lifter bars or knives, and *g g'* the levers for lifting the machine, each actuated by rods *g² g³* from the crank-shaft of the loom, the said parts being usual to cross-bordering or two-cylinder machines and so far only differing from ordinary two-cylinder machines in respect of the arrangement of the two cylinders *b c* on one and the same side of the machine and the construction of the auxiliary set of needles *c'*, which, instead of being looped or cranked at two separate points to receive the uprights *e e*, as in the case of the ordinary needles *b'*, are formed with a single extended bent-out portion *c²*, within one end of the recess formed by which one of the uprights *e* registers on one side of the needle, while the other corresponding upright of the pair registers in the angle at the outer opposite end of the recess on the contrary side of the needle, this construction of the auxiliary needles *c'* permitting of free movement of the uprights *e e* when actuated by the needles *b'* from cylinder *b* without being affected thereby and being adapted to operate said uprights when the cylinder *c* is in action, these said auxiliary needles forming the subject of a previous application filed by me on November 17, 1900, Serial No. 36,831. I have shown my invention applied to this description of two-cylinder machine because I prefer it by reason of its simplicity and effectiveness.

On the contrary side of the jacquard to the cylinders *b c* I mount, respectively, on studs *h' i'*, carried by a bracket bolted to the frame

a or to the beam *a'* and which is omitted for the sake of clearness, two bell-crank cylinder-operating levers *h i*, having their vertical arms coupled by links or rods *h² i²* to rods *h³ i³*, attached to the cylinders *b c*. The horizontal arms of said bell-crank levers carry in slotted bearings at their extremities studs or rolls *h⁴ i⁴*, which project through respective elongated slots *j' j²* in the usual cylinder-rod *j*. Centered on a stud *k'*, secured to the cylinder-rod *j* and on which it is free to turn, is a double cylinder-lever catch or sneck *k*, having at its opposite extremities catches or hooked snecks *k² k³*, which are adapted, as hereinafter explained, to engage one at a time with the respective studs or rolls *h⁴ i⁴* on the bell-crank levers *h i*. On a stud *l*, secured to the same bracket which carries the bell-crank cylinder-operating levers *h i*, is mounted a four-armed or star lever *m*, to the arms *m' m²* of which are attached one end of links or rods *n n*, whose opposite ends are secured to the double-catch lever *k* on opposite sides of its pivot *k'*. To the remaining two arms *m³ m⁴* of the four-armed lever *m* are secured cords or flexible connections *o o'*, which are attached at their lower ends to respective drop pins or bars *p q*, supported and guided vertically in bearings in a bracket *r*, bolted to a convenient part of the loom-framing. These drop-pins normally rest on the peripheries of respective cams or rings *p' q'*, mounted on a shaft *s* or secured to a face-plate *t* on said shaft *s*, and they have spiral springs *p² q²* surrounding same and confined between collars *p³ q³* thereon and the upper part of the bracket *r*, these springs being compressed when the pins rest on the longer radii or periphery of the cams or rings *p' q'*. The face-plate *t* forms an indicating-plate and is marked off to scale radially to indicate inches and yards or other system of measurement adopted. The cams or rings *p' q'* are made with recesses or cut-outs *p⁴ q⁴*, (see Fig. 2,) ordinarily one in each cam, and the straight radial sides of said recesses or cut-outs are set to coincide with the figures or indication of measurement on the scale at which they must respectively be brought under the corresponding drop-pins for the purpose of bringing about a change of cylinder after weaving the predetermined length of fabric. Fast on the shaft *s* is a spur-wheel *s'*, with which meshes a change-pinion *s²*, mounted on a stud-shaft *s³*, carrying a chain-wheel *s⁴*. A chain *u*, driven by a chain-wheel *v*, fast on the positive or cloth roller shaft *v'* and guided under guide-rollers *w w*, conveys a positive motion to the chain-wheel *s⁴* and through change-pinion *s²* and spur-wheel *s'* to the shaft *s*, whereby the indicating-plate *t* and cams or rings *p' q'* are rotated in a degree corresponding to the motion of the positive roller, the rotation of the latter to take up a given length of fabric giving, by means of the change-pinion *s²* employed, one complete revolution to the plate *t* and cams

p' q' in the weaving of a predetermined length of fabric. Thus, for example, if the length of fabric to be woven to complete a center portion and cross-bordering of a carpet-square or shawl or a pattern or figure and ground intervening between same and the next pattern or figure or two entirely different figures or patterns should be four yards altogether, two yards for the center and two yards for the cross-borders between one center portion and the next center portion, the cams will be moved to the extent of one revolution in weaving the said four yards, and the recess or cut-out in cam p' will be presented to its drop-pin p when two yards have been woven and the recess or cut-out in cam q presented to its drop-pin q when the remaining two yards have been woven—that is to say, the setting of the cams with respect to the scale of measurements on plate t , which may vary to any extent within said scale, will bring about a change of cylinder after weaving any given length of fabric from five picks upward and two changes during one complete revolution of the cams p' q' —namely, from the first to the second cylinder and then from the second cylinder back to the first in readiness for the next succeeding length. When the total length of fabric to be woven to include a center and cross-bordering varies by increase or decrease of measurements, a change-pinion having a larger or smaller number of teeth than the pinion s^2 is geared to the spur-wheel s' , so that the cams p' q' shall be rotated one revolution during the taking up of the increased or reduced length of fabric by the positive roller.

The action of the mechanism described and shown in the drawings for controlling the changing of the cylinders is as follows: The cylinder-rod j is caused to move vertically up and down in the usual manner by an eccentric on the crank-shaft and carries with it the double-catch lever k , whose position determines which of the bell-crank levers h i and respective cylinders b c shall be actuated. In Fig. 1 the cylinder-rod j is shown at its highest position, with the catch-lever k moved over to present the upper catch or sneck k^3 directly over the stud or roll i^4 , projecting through the slot j^2 from bell-crank lever i , and the lower sneck or catch k , clear of the roll or stud h^4 , projecting through the slot j' from the bell-crank lever h . In the next downward stroke of the cylinder-rod j the catch k^3 will engage with the stud or roll i^4 and carry it down to the extent of its movement, thereby rocking the bell-crank lever i on its center i' and drawing the cylinder c forward against the needles c' to actuate same according to selection of the card presented thereto by the cylinder, the stud or roll h^4 on lever h during this movement riding freely within the limits of the slot j' , so that the bell-crank lever h remains stationary in the position shown. In the upward stroke of the cylinder-rod j the lower sneck or catch k will engage with the roll or stud h^4 and carry it up to the extent of its movement, thereby drawing the bell-crank lever h forward against the needles h' to actuate same according to selection of the card presented thereto by the cylinder, the stud or roll i^4 on lever i during this movement riding freely within the limits of the slot j^2 , so that the bell-crank lever i remains stationary in the position shown.

der-rod j the roll i^4 is engaged by the lower end of the slot j^2 and the lever i moved back to its original position, as shown. By the time the length of fabric constituting the cross- 5 bordering or ground or alternate figure or pattern has been woven the rotation of the cam p' has brought the recess or cut-out p^4 under the drop-pin p , which is instantly forced down by its spring p^2 into said recess until 10 the head of the pin engages with the bracket r , the descent of the drop-pin p through the cord connection o turning the four-armed lever m on its center in the direction of the arrow and through links $n\ n'$ reversing the 15 position of the double-catch lever k , which now places the lower catch or sneck k^2 into the path of the stud or roll h^4 on the bell-crank lever h , whereby at each successive downstroke of the cylinder-rod j the bell-crank 20 lever h is actuated to draw the cylinder b forward against the needles b' and bring a separate chain of cards into play, the successive upstrokes of rod j moving the cylinder b back to its outer position. One of the arms of the 25 four-armed lever m , as the arm m' , is provided with two projecting flat surfaces $m^5\ m^6$, and a flat spring m^7 is secured to the bracket which carries the said lever and bell-crank levers $h\ i$, this spring bearing against one of 30 said flats, according to the position into which the four-armed lever is moved, and preventing any abnormal movement thereof when turned into either of its two positions. The actuation of the cylinder b continues 35 until the length of fabric constituting the center portion of the carpet or shawl or the pattern or figure has been woven, and by the time this takes place the rotation of cam q' has brought its recess or cut-out q^4 under the 40 drop-pin q , which is instantly forced down by its spring q^2 , and through cord connection o' draws down arm m^4 and turns the four-armed lever on its center back into the position shown at Fig. 1 and through links $n\ n'$ oscillates 45 the catch-lever k to place the upper catch or sneck k^3 again into position to engage the roll i^4 on lever i to bring the cylinder c into action to weave the next cross-bordering or ground. The drop-pins $p\ q$ after 50 their descent are raised again to their normal positions by the cam-surfaces on the cams or rings $p'\ q'$, over which they ride as the cams continue to rotate. The rods $h^3\ i^3$, connected to the cylinders $b\ c$, are surrounded at one end 55 by spiral springs $h^5\ i^5$, confined between collars $h^6\ i^6$, secured on said rods, and the bearings $h^7\ i^7$, these springs serving to keep the cylinders steady when not in action. When there are no definite lengths of fabric to be 60 woven between each change of cylinder required, as in weaving at will either one and one or two and one or any similar order of picks—such as in Madras, muslin, or similar figured or fancy goods—the measuring mechanism above described is not necessary, and the cords $o\ o'$ may therefore for the time being disconnected at one end from the part 65 to which attached. In lieu of said measuring mechanism I attach a rod x , Fig. 4, secured to one arm of a bell-crank lever x' to the arm m' of the four-armed lever m , and the other arm of the bell-crank lever x' is secured to the harness attached to one selected pair of uprights $e\ e$, which are actuated at the proper time, according to selection of the pattern-cards, to bring about a change of cylinders. 70 When the uprights are lifted, as usual, on being called for by the pattern the bell-crank lever x' is oscillated and through rod x moves the four-armed lever m on its center in the direction of the arrow, whereby through rods or links $n\ n'$ the position of the catch-lever k is reversed to place cylinder c out of action and bring cylinder b into action. On the uprights being released 75 they are drawn down to their lowest positions by a retracting-spring x^2 , secured at one end to the bell-crank lever x' and at the opposite end to a fixed stud, the four-armed lever m then being moved back into the position 80 shown and the cylinders changed. In weaving goods requiring every second shot to be a ground-shot the two cylinders can be brought into action alternately throughout the weaving of the fabric by connecting the two arms 85 $m^3\ m^4$ of the four-armed lever m to the lifting-levers $g\ g'$, as shown at Fig. 5. The two subsidiary connections between the four-armed lever m and a double lift of the harness or head-motion or the lifting-levers, described and shown at Figs. 4 and 5, are useful to provide for controlling the changing 90 of the cylinders in weaving fabrics in which the measuring-motion cannot be employed to advantage, and as each can be easily connected or disconnected at will and do not encumber the machine it is advantageous that such provision should be made in two-cylinder machines having the measuring-motion applied, whereby either of the two supplementary forms of connection can be adopted 95 to suit different weaves when the measuring-motion is not of service to the class of goods to be woven. 100

I claim—

1. In a jacquard mechanism, the combination, with two pattern-cylinders, and separate levers and intermediate mechanism for operating them independently; of a rod for operating the said levers, a double catch for 105 connecting the said rod with the said levers alternately, and trip mechanism operating automatically at prearranged intervals to reverse the connection of the said double catch, substantially as set forth. 115

2. In a jacquard mechanism, the combination, with two pattern-cylinders, and separate levers and intermediate mechanism for operating them independently; of a rod for operating the said levers, a double catch pivoted to the said rod and connecting it with the said levers alternately, two cams and driving mechanism for revolving them continuously, two spring-actuated drop-pins 120

125

130

bearing respectively against the said two cams, and intermediate connections between the said drop-pins and the double catch whereby the said double catch is operated periodically, substantially as set forth.

3. In a jacquard mechanism, the combination, with two pattern-cylinders, and separate levers and intermediate mechanism for operating them independently; of a rod for operating the said levers, a double catch pivoted to the said rod and connecting it with the said levers alternately, a pivoted four-armed lever, connections between two of the opposite arms of the four-armed lever and

the said catch, means for holding the four-¹⁵ armed lever against abnormal movement, and two independent tripping devices operated automatically at prearranged intervals and connected with the remaining arms of the said four-armed lever, substantially as set ²⁰ forth.

In testimony whereof I affix my signature in presence of two witnesses.

WALTER PATON.
